HYDRAULIC DEVICE

William M. Osborn, 3349 Zuni St., Denver 11, Colo.
Filed Jan. 24, 1958, Ser. No. 710,959
5 Claims. (Cl. 103—136)

This invention relates to an improved hydraulic device, and particularly to an improved positive displacement pump of sturdy and simple construction for delivering one or several fluids in high volume and at relatively high pressure while operating at a relatively low speed. The device may also be utilized as a fluid motor and as a combined fluid motor and pump.

An object of the invention is to provide a device of the type described, which is dynamically and hydrostatically balanced so that it will operate smoothly and efficiently with a minimum amount of wear on the moving parts.

Another object of the invention is to provide a device of the type described in which close operating tolerances between the moving parts may be maintained.

Another object of the invention is to provide a positive displacement pump which can pump two fluids at the same time and at the same or at different pressures.

Another object of the invention is to provide a positive displacement pump which can be used to pump a fluid having an extremely high or low temperature while the operating parts of the pump may be maintained within a less extreme temperature range.

Another object of the invention is to provide an improved radial-vaned rotary pump which can be operated with equal efficiency in either direction.

Another object of the invention is to provide an improved radial-vaned rotary pump which can be operated as a two-stage pump for a single liquid, as a pump for two different liquids, or as a combined pump and motor.

Still further object of the invention is to provide improved means for facilitating the opening and closing of the rotor vanes of an hydraulic device having rotor vanes which are radially movable.

These and other objects and advantages of the invention will be apparent from the following description taken in conjunction with the drawings in which

FIG. 1 is a front elevational view of the hydraulic device of the present invention;

FIG. 2 is a side view of the device shown in FIG. 1;

FIG. 3 is a sectional view of the hydraulic device of FIGS. 1 and 2, taken on the line 3—3 of FIG. 2, and showing in detail the construction and arrangement of the rotor unit and an associated housing section;

FIG. 4 is a sectional view taken on the line 4—4 of FIG. 3 and further showing the manner of mounting the rotor unit with respect to its associated housing elements;

FIG. 5 is a perspective view of the rotor unit with the vanes removed;

FIG. 6 is a perspective view of one of the rotor vanes adapted to be mounted within one of the recesses of the rotor shown in FIG. 5;

FIG. 7 is a fragmentary view of a modified form of an adjustable abutment which can be used in the device illustrated in the preceding figures; and

FIG. 8 is an elevational view, partially diagrammatic, showing one of the ways in which the hydraulic device of the preceding figures may be used.

Referring now to the drawings in detail, and particularly to FIGS. 1, 2 and 3 thereof, the hydraulic device of the present invention is shown to comprise a pair of plate-like end housing sections 12 and 14 having disposed therebetween an annular or ring-like intermediate housing section 16. The intermediate housing section 16 is formed integrally with a base 18 whereupon the device

2

may be mounted upon a suitable support 20 by means of bolts 22. The housing sections 12, 14 and 16 are secured together in tightly assembled relationship by a plurality of bolts 24, which pass through suitable registering openings in the respective housing sections, and nuts 26 threadedly engaging the ends thereof.

The end housing sections 12 and 14 are provided with central openings 28 in which a shaft 30 is journaled. It will be understood that the end housing sections 12 and 14 may be provided with outwardly extending hubs and with suitable bearings (not shown), if so desired. However, it has been found that in small devices machined for close operating tolerances, such means are not necessary. The openings 28 through the end plates 12 and 14 are of a very slightly greater diameter than the diameter of the shaft 30, so as to provide close operating clearance only, thereby with certain other close-fitting parts described hereinafter preventing leakage of fluid from the device and rendering the provision of separate seal means unnecessary.

Referring now particularly to FIGS. 3 and 4, it will be seen that the housing sections 12, 14 and 16 form a rotor chamber housing a cylindrical rotor 32. The width of the rotor 32 is substantially the same as the width of the annular housing section 16 between the end sections 12 and 14, so that the side faces 34 of the rotor 32 confront the inner faces 36 of the end housing sections 12 and 14 with only very close operating tolerance therebetween. The closely fitting rotor contributes to the effective sealing of the device against liquid leakage around the shaft 30.

The rotor chamber has an inner periphery 38 formed within the annular housing section 16, which is concentric with the periphery 40 of the rotor 32 and is sufficiently spaced therefrom to provide working chambers 42 and 44 for radially movable vanes 46, 46a, 46b, 46c, 46d and 46e carried by said rotor 32. Portions of the inner periphery 38 of the annular housing section 16 are removed to form a pair of diametrically opposed, relieved portions 48 and 50. The relieved portions 48 and 50 may extend the full width of the annular housing section 16 and may be concentric with the periphery 40 of the rotor 32. Shoulders 51, 51a, 51b and 51c define the beginning and ending of the relieved portions. The function of the relieved portions 48 and 50 is to facilitate retraction of the rotor vanes 46, 46a, etc., at the discharge end of a working chamber, as will hereinafter be more fully described.

The outer periphery of the annular housing section 16 is provided with a pair of oppositely disposed, enlarged portions or bosses 52 and 54, which are substantially in registry with the internal relieved peripheral portions 48 and 50.

In accordance with a special feature of the present invention, the internal peripheral portions of the housing section 16 intermediate the relieved areas 48 and 50 (FIG. 3) are provided with radially movable, adjustable abutments 56 and 58 mounted within recesses 60 and 62 formed in the enlarged portions 52 and 54. The recesses 60 and 62 and abutments 56 and 58 extend for the full width of the housing section 16, and the abutments 56 and 58 define the ends of the working chambers 42 and 44. The abutments 56 and 58 are provided with inner ends 64 and 66, which have an arcuate configuration corresponding to the cylindrical periphery 40 of the rotor 32, so that they may closely engage the rotor periphery 40, as shown.

The abutments 56 and 58 are radially movable within their recesses 60 and 62 and means are provided to control the degree of adjustment toward the rotor periphery 40. Such means, as shown in FIG. 3, comprise adjusting bolts 68 and 70, which threadedly engage bores 72

and 74 in the housing section 16. The bolts 68 and 70 at their inner ends are received with smooth bores 76 and 78 formed within the abutments 56 and 58 and are free to rotate therein. Lock nuts 80 and 82 are provided so that the adjusting bolts 68 and 70 may be tightly secured in the proper adjusted position. Accordingly, it will be seen that by means of these bolts the abutments 56 and 58 may be urged into contact with the rotor periphery 40 and may then be locked into such position. It will be understood that the degree of pressure with which the abutments contact the rotor periphery is adjusted so that there is no substantial interference with the free rotation of the rotor 32. Readjustments may be made from time to time to compensate for any wear on the relatively movable parts.

In a modified form of the invention, as shown in FIG. 7, a radially movable abutment 84 may be disposed in a recess 86 in the annular housing section 16 and may be resiliently urged toward the rotor periphery 40 by means of a spring 88 held within a bore 90 in the housing section 16 by means of a threaded plug 92. The structure of the oppositely disposed abutment is, of course, identical to the single illustrated form. By such means, the abutments are constantly urged into engagement with the rotor periphery 40 to thereby insure a positive seal, preventing leakage of fluid between abutment and rotor.

Referring now to the rotor 32 it will be seen, particularly from FIG. 5, that this rotor is provided with a plurality of radial slots or recesses 94, which extend for the entire width of the rotor body. The recesses 94 are provided in oppositely disposed pairs so as to insure dynamic balance of the rotor 32 for smooth rotor operation. Each recess 94 is provided with a rotor vane 46, or 46a, 46b, etc. (FIG. 3), which is of the same width as the rotor 32, so that the side faces 96 of the rotor vanes are flush with the side faces 34 of the rotor 32. The peripheral ends 98 of the rotor vanes 46, 46a, 46b, etc., are provided with substantially the same arcuate configuration as the inner periphery 38 of the housing section 16 which they contact when fully extended, for example, when in the position of the rotor vanes 46 and 46c, FIG. 3. The bottom ends 99 of rotor vanes 46, 46a, 46b, etc., are substantially spaced from the bottom 100 of the rotor recesses 94, even when such vanes are retracted to a position such that the peripheral ends 98 are flush with the rotor periphery 40. The purpose of this spacing is to facilitate the outward movement of the vanes, as will be later described in detail.

The lower portion of each rotor vane 46, 46a, 46b, etc., is provided with a bore 101 to accommodate a shaft 102 (FIG. 4). The ends of the shaft 102 are provided with rotatable cam followers 104, which may be mounted by means of roller bearings 106 for smoother operation.

The inner face 36 of each of the end housing sections 12 and 14 is provided with a cam track 108 which, as particularly shown in FIG. 3, communicates with lower portions of the rotor recesses 94 and receives cam followers 104 of the rotor vanes 46, 46a, 46b, etc. The configuration of the cam tracks 108 is such that the rotor vanes 46 are permitted to be extended radially outwardly, fully into contact with the inner periphery 38 of housing section 16 during angular movements of the rotor throughout the arcuate length defined by the periphery 38. The cam track 108 changes in its path, as at 110, 111, 112, and 113, so that (assuming the rotor is turning counterclockwise as shown in FIG. 3) as rotor vanes 46, 46a, 46b, etc., reach shoulder 51 defining the beginning of relieved section 48, or 51b defining the beginning of a relieved section 50, the vanes are permitted to retract, becoming fully retracted when they pass the abutments 56 or 58, as the case may be, and are then permitted to become fully extended as they reach shoulders 51a and 51c.

The enlarged sections 52 and 54 of the housing sec-

tion 16 are provided with openings 114—115 and 116—117 disposed on each side of the abutments 56 and 58, respectively, so as to provide for the flow of fluid through the working chambers 42 and 44 of the device. These 5 openings 114—115 and 116—117 are threaded at their ends and are provided with conventional pipe fittings 118. When the rotor 32 is turning in a counterclockwise direction as viewed in FIG. 3, opening 116 constitutes the inlet opening for flow of fluid into working chamber 42 and opening 114 constitutes the discharge opening for this fluid. Likewise, opening 115 constitutes the inlet opening for flow of fluid into the second working chamber 44 and opening 117 constitutes the discharge opening for this working chamber. Where 15 the rotor 32 is to be run in the reverse or clockwise direction as viewed in FIG. 3, the inlet and discharge openings to the respective working chambers 42 and 44 are, of course, reversed—openings 114 and 117 becoming inlet openings and openings 116 and 115 becoming discharge openings. Since all parts are exactly symmetrical, it makes no difference as to the direction in which the rotor is turned.

In operation of the device as a pump, assuming counterclockwise rotation of the rotor 32 (FIG. 3), fluid 25 enters inlet opening 116, is picked up by a rising vane such as a vane in the position of that designated as 46e, is carried around the working chamber 42 by such vane which becomes fully extended to the position shown by the vane indicated by the numeral 46, and is then forced 30 out of the discharge opening 114. At the same time, fluid entering through the opening 115 is being picked up by the vanes as they travel through working chamber 44 and is discharged through the opening 117. The 35 vanes 46, 46a, 46b, etc., once fully extended so that their ends 98 contact the inner housing periphery 38, as in the position of the vanes indicated by the numerals 46 and 46c shown in FIG. 3, do not retract until they pass shoulders 51 and 51b approaching the discharge openings. Centrifugal force facilitates the holding of the 40 vanes in this outward position and the cam means, comprising the cam track 108 and cam followers 104 prevent retraction should this force be insufficient. Fluid at discharge pressure then reacts downwardly upon the ends 98 of the vanes as they clear shoulders 51 and 51b and cause them to retract. The curvature of the cam tracks 45 at, for example, 110 and 112 prevents retraction of the vanes with a shot-like action and the cam path then assures that the vanes remain retracted while they pass abutments 56 and 58. The vanes are then extended as they clear the abutments and approach shoulders 51a and 51c by a combination of centrifugal force acting against the relatively low intake pressure and the camming action of the cam followers 104 and cam track at 111 and 113.

The cam track 108 performs a further important function in facilitating the movement of the vanes during rotation of the rotor. Thus, as previously mentioned, the cam track interconnects the bottom portion of the recesses 94 in the rotor 32 and permits the passage of fluid therebetween. Accordingly, as one vane, for example vane 46a, retracts within its recess, fluid in the bottom portion of such recess is displaced through the cam track 108 into the bottom of a recess beneath a rising vane, as for example 46b, and helps to push this vane to its outward position. Accordingly, the vanes are operated to a large extent in their retraction and opening by fluid pressure and centrifugal force, the cam path 108 and cam followers 104 serving as an additional control factor to insure that the vanes are in proper position at all times. It will be seen that oppositely disposed vanes are always in the same relative position, thereby maintaining the rotor in perfect dynamic balance. It will be noted, with reference to FIG. 3, that the spacing of the vanes 46, 46a, 46b, 46c, 46d and 46e, and the configuration of the cam tracks 108, are so related that

the total volume of the clearances beneath all of the vanes remains constant, that is, as one or more vanes move inwardly, another vane or vanes move outwardly at a rate to maintain a constant volume of the total of the clearances. It will also be noted that the vanes have a length which is shorter than the length of the recesses, so that, when they are fully retracted, a clearance remains beneath the vanes, and that these clearances are always in communication with the cam tracks. The clearances and the cam tracks, therefore, constitute a closed system which remains constant in volume. Since no sealing means are provided between the rotor and the side walls 12 and 14, there will be a slight leakage from the high pressure side toward the cam tracks and the clearances beneath the vanes, and a slight leakage from the cam tracks and the clearances beneath the vanes toward the low pressure side. The clearances and the cam tracks will therefore be filled with fluid at a pressure intermediate the high pressure side and the low pressure side, which pressure will act radially outwardly on the bottom of the vanes. As the volume constituting the clearances and cam tracks will remain constant, as explained above, the pressure will also remain substantially constant. By virtue of this arrangement, the end thrusts on the vanes are approximately one-half of what they would be if no fluid were trapped in the clearances and cam tracks, thereby reducing wear on the cam followers and cam tracks and requiring less work to operate the device as a pump, and offering less resistance when used as a motor. The clearances beneath the vanes provide passages for the fluid to pass from one side of the cam followers 104 to the other side.

In operating the device as a two-stage pump for a single fluid, the discharge opening 114 may be connected by means of suitable piping (not shown) to the intake opening 115. Fluid entering at 116 is then pumped through the one working chamber 42, out the discharge opening 114 into the inlet opening 115, through working chamber 44 and out of the discharge opening 117. In operating the device as a pump for two different liquids, the inlets 116 and 115 are, of course, connected to different sources of fluid.

Another manner of operating the device as a pump is illustrated in FIG. 8. In accordance with this manner of operation, an extremely hot liquid which normally might overheat the pump parts and interfere with proper operation, enters through inlet pipe 120 and is pumped through chamber 44 of the pump, and out of outlet pipe 122. In order to prevent the rotor and other moving parts from overheating, the device is cooled by circulating a cooling liquid through the other working chamber 42 from inlet pipe 124, then out of a discharge pipe 126 through a heat exchange coil 128, where heat is given off to a suitable cooling fluid entering through pipe 130 and out of pipe 132, and then back through the inlet pipe 124. The rotor is effectively cooled by running in direct contact with the cooling fluid during one-half of each complete revolution. It will be understood, of course, that recirculation of cooling fluid through the heat exchanger can be omitted, if desired, where a suitable source of cooling fluid is constantly available. For example, it may be desired in some cases to pump a hot liquid through one chamber while the pump is being cooled by another cooler liquid pumped through the other chamber for delivery to a specific usage. The double chamber pump of the invention is adaptable to a wide variety of such uses.

In the foregoing illustrations of operation of the device it has been assumed that the rotor shaft 30 would be driven by a separate motor or other means (not shown), and that pump action would be effected in both working chambers. However, in accordance with another arrangement, fluid may be forced through one of the working chambers to drive the rotor, and the other working chamber may be utilized as a pump. Thus,

cooling fluid under pressure might be utilized to both cool the rotor and impart rotary motion to such motor for pumping hot liquid through the other working chamber. It will also be understood that the device can be used as a fluid motor by supplying fluid under pressure to both inlet openings. The rotor may be driven in either direction with equal facility. The device may be used to pump fluids at low pressures or at pressures as high as 10,000 pounds per square inch, or greater. One relatively small unit has been found to deliver about 23 gallons of liquid per minute at 5000 p.s.i.g. when the shaft is turned at 600 r.p.m. None of the parts works against conflicting hydraulic pressures, and all revolving parts are in complete balance. The device may be fabricated to fit any installation, large or small. Thus, it is readily adaptable to units designed to deliver from less than one gallon per minute up to 5,000 gallons per minute, or greater.

It will be understood that various changes which will occur to those skilled in the art may be made without departing from the principles of the invention or the scope of the annexed claims.

I claim:

1. A hydraulic device, comprising: a housing having side walls and an annular member forming a rotor chamber; a shaft journaled in said side walls and extending through said rotor chamber; a rotor in said chamber fixed to said shaft, said rotor having a plurality of recesses extending radially inwardly around the periphery thereof for the full width of said rotor; vanes mounted in said recesses for radially inward and outward movement with respect to said rotor, said rotor chamber being concentric with the rotor and having a diameter greater than that of said rotor forming a working chamber surrounding the rotor to accommodate the radially outward movement of said vanes; means in a side wall forming a closed, liquid-filled channel separated from the working chamber connecting the lower portions of said recesses for fluid pressure equalization below said vanes, said vanes having a radial length shorter than the radial length of the recesses so that, when in their retracted position with the outer ends of the vanes flush with the periphery of the rotor, the inner ends of the vanes provide a clearance permitting an uninterrupted connection between the respective recesses and the channel at all times, the vanes being related with each other so that, as one or more vanes move outwardly, another or other vanes move inwardly to maintain the total volume of the recesses beneath the vanes constant; a pair of diametrically opposed, radially movable abutments mounted within said housing and extending inwardly from the periphery of said rotor chamber and adapted to contact the periphery of said rotor to thereby define the limits of a pair of working chambers for said rotor vanes; means for adjusting the radial position of said abutments with respect to said rotor; and fluid inlet and outlet means through said housing on each side of said abutments.

2. The hydraulic device of claim 1 wherein said means for adjusting the radial position of said abutments with respect to said rotor comprise resilient means urging said abutments into contact with said rotor periphery.

3. The hydraulic device of claim 1 wherein said channel means for connecting the lower portions of said rotor recesses comprise a cam track in the housing and wherein said rotor vanes are provided with cam followers cooperating with said cam track to thereby control inward and outward movement of said rotor vanes.

4. The hydraulic device of claim 1 wherein said housing has a portion of its inner periphery relieved adjacent the discharge ends of the working chambers, whereby fluid at discharge pressure may act upon the outer end of the rotor vanes as they approach the abutments to thereby cause said vanes to retract within their recesses.

5. A hydraulic device, comprising: a housing having side walls and an annular member forming a rotor chamber; a shaft journaled in said side walls and extending through said rotor chamber; a rotor in said chamber fixed

to said shaft, said rotor chamber having a diameter greater than that of said rotor to form a fluid chamber surrounding said rotor; a pair of spaced abutments carried by said housing and extending across said fluid chamber to divide said chamber into two separated sections; movable vanes, carried by said rotor, and extending into said fluid chamber to form, in cooperation with said abutments, expandable and contractible working chambers; fluid inlet and outlet means for each section on each side of said abutments; the inlet means to one of said sections connected to a source of fluid at a very high or very low temperature; means to connect the inlet and outlet means of the other section in a closed circuit independent of said one of said sections; and a heat exchange means in said closed circuit.
